Inventor:

George B. Heath,
by E. M. Bond

UNITED STATES PATENT OFFICE.

GEORGE B. HEATH, OF SAN FRANCISCO, CALIFORNIA.

COIN-CONTROLLED TELEPHONE-CALL APPARATUS.

SPECIFICATION forming part of Letters Patent No. 635,852, dated October 31, 1899.

Application filed October 31, 1898. Renewed October 4, 1899. Serial No. 732,574. (No model.)

To all whom it may concern:

Be it known that I, GEORGE B. HEATH, a citizen of the United States, residing at San Francisco, in the county of San Francisco and State 5 of California, have invented certain new and useful Improvements in Coin-Controlled Telephone-Call Apparatus; and I do hereby declare the following to be a full, clear, and exact description of the invention, such as will 10 enable others skilled in the art to which it appertains to make and use the same.

This invention relates to certain new and useful improvements in coin-controlled apparatus and is designed more particularly for 15 use in connection with telephones to prevent defrauding of the telephone company.

It has for its objects, among others, to provide an improved construction of this character by which the operator at the central office can readily tell if the box is being tampered with and have it under his or her control, so that the company cannot be defrauded, the construction that forms the subject-matter of this application being such that if a 25 wire or a piece of metal be put down the coin-slot it will short-circuit the two main lines and put out the light or affect the other signal in the central office. If the light should stay lighted after the key at the central office 30 is pressed or go out before the key is actuated, it will indicate that some one is tampering with the box. I aim to make the construction as simple as possible, yet positive in its action, so that it will be reliable.

Other objects and advantages of the invention will hereinafter appear, and the novel features thereof will be specifically defined by the appended claims.

The novelty in this instance resides in the 40 peculiar construction and the combination and arrangement of parts, all as more fully hereinafter described, shown in the drawings, and then particularly pointed out in the claims.

The invention is clearly illustrated in the accompanying drawings, which, with the letters and figures of reference marked thereon, form a part of this specification, and in which—

Figure 1 is a view, partly in side elevation and partly in vertical section, showing the improvement and a diagram of the electrical

connections with the central office. Fig. 2 is an edge view of the coin chute and balance with portions in section.

55

Like letters of reference indicate like parts in both views.

Referring now to the details of the drawings by letter, A designates a box or casing within which the operating parts of my apparatus are arranged. In the top of this box or casing is a slot or opening which communicates with the upper portion B of the chute, which in turn communicates with the lower portion C of the said chute. The upper and 60 lower portions B and C are insulated from each other by the block D, of insulating material, and which serves in a measure to support the lower portion, as shown. These two portions of the coin-chute are connected to 65 each side of the main line, as seen in Fig. 1.

E is a plate, the lower edge of which is preferably serrated, as seen in Fig. 1, and this plate is pivotally mounted, as at F, in the side walls of the lower portion of the coin-chute, as seen in Fig. 2, and extending from this pivot is an arm or rod G, which is adapted to move with the plate, and upon this rod, which is by preference screw-threaded, is a weight H, the weight being adjustable 70 on the rod, so that the same may be moved when desired to vary the ease with which the said plate may be moved. This plate normally extends across the passage through the chute, as seen in Fig. 2, so as to prevent the 75 introduction of a wire or any means to withdraw the coin or to attempt to depress the balance soon to be described. It is so counterbalanced as to move by the weight of the coin thereon and then to move back to its 80 former position by reason of the weight H.

I is an arm or lever pivotally mounted between its ends, as at J, within the box or casing and carrying at one end beneath the lower end of the coin-chute a plate J', from 95 the side of which projects a pin K in such position as to be directly beneath the discharge of the lower portion of the coin-chute, as seen best in Fig. 2, and upon which the coin is designed to fall as it drops from the chute. 100 From this point the coin is designed to drop into a cash-receptacle L, suitably supported within the box or casing, as seen in Fig. 1. The opposite end of this arm or lever carries

the armature M, as seen in Fig. 1, which is designed for coöperation with the magnet N, suitably supported within the case and connected up as shown in Fig. 1.

5 O is a contact-point adjustably mounted on the arm or lever I between its pivot and the end carrying the armature, and this contact is designed for coöperation with the contact P, carried by the free end of the spring P', 65 suitably supported within the box, as seen in Fig. 1.

Q is a key, and R is a lamp located at the central office.

S is a battery.

15 The parts are connected up as follows: The wire 1 runs from the battery to the key Q and from the other pole of the battery to the binding-post 2, within the box or casing A. From this binding-post the wire connects

20 with the coils of the magnet or solenoid and from the other end to the spring P'. The wire 3 runs from the contact T of the key Q to the lamp and from the lamp to the binding-post 4. From this binding-post a wire

25 connects with the lower portion of the coin-chute, and another wire 5 connects this binding-post with the pivot of the arm or lever I, all as clearly seen in Fig. 1.

6 is a wire connecting the binding-post 2

30 with the upper portion of the coin-chute.

U is a spring having one end secured to some fixed part and its other end attached to the arm or lever I between its pivot and the end that is beneath the coin-chute and serving to normally keep the said end elevated, 95 as will be readily understood.

With the parts constructed and arranged substantially as above set forth the operation will be readily understood, especially when

40 taken in connection with the annexed drawings. Briefly stated, it is as follows: Fig. 1 represents the parts in their normal position. When the coin is dropped in the slot, it passes down past the catch-plate E, and as it comes

45 in contact with the pin or projection K on the balance-lever it moves the same downward and brings the other end of the lever upward, bringing the contact O up against the contact P, which completes the circuit through

50 the coil or magnet. When the current goes through the coils, it magnetizes the core X, which attracts the armature M, keeping the points O and P together until the circuit is opened by the operator at the key Q in the

55 central office. When the circuit is opened by the manipulation of the key, the core loses the armature, and the weight of the balance-lever causes the two contact-points to separate, thus putting out the lamp at the cen-

60 tral office. Should a wire or a piece of metal be put down the slot, it would short-circuit the two main lines and cutting out the coil prevent the working of the box. If the wire

should be pulled out, the light would go out without the central-office operator touching the key. The light should stay lit until the key is depressed.

The serrated catch-plate serves most effectively to prevent any tampering with the box without notifying the central office.

Modifications in detail may be resorted to without departing from the spirit of the invention or sacrificing any of its advantages.

What I claim as new is—

1. In a device of the character described, a 75 coin-chute in sections with the sections separated horizontally and insulated from each other by an insulating-block supporting the lower section said sections being connected with the main lines, and a lamp and key in 80 circuit with the main lines, all substantially as shown and described.

2. In a device of the character described, the combination with the coin-chute in sections insulated from each other, of the pivoted lever, 85 the projection at one end at right angles to the length of the lever, the armature at the other end, the vertically-adjustable contact carried by said lever between its pivot and armature, the relatively-fixed contact, the 90 lamp and key, and the coil and electrical connections, substantially as and for the purpose specified.

3. In a device of the character described, the combination of a coin-chute in sections insulated from each other, a pivoted lever with one end beneath the chute and carrying a projection at right angles to the length of the lever to be engaged by a coin, an armature on the other end of the lever, a contact carried by 100 said lever between its pivot and armature, a relatively-fixed contact for coöperation therewith, a coil for coöperation with said armature, a lamp and key, connections between the sections of the coin-chute and the main 105 line, and connections between the lever, fixed contact and the coil, all substantially as and for the purpose specified.

4. The combination of the coin-chute in sections insulated from each other, the pivoted 110 lever, its plate and projection at right angles to the plate, the armature and contact carried by said lever, the contact being between the pivot of the lever and its armature, the relatively-fixed contact carried by a spring- 115 arm, and electrical connections with a lamp and key in the main line, whereby tampering with the device is indicated at the central office, substantially as described.

In testimony whereof I affix my signature 120 in presence of two witnesses.

GEORGE B. HEATH.
